CIRCUIT BREAKER AND ENERGY
ABSORBER THEREFOR

George A. Healis, Philadelphia, Pa., assignor to
I-T-E Circuit Breaker Company, Philadelphia,
Pa., a corporation of New Jersey

Application August 29, 1936, Serial No. 98,562

21 Claims. (Cl. 200—166)

My invention relates to circuit interrupters, particularly to automatic high speed circuit breakers, and has for an object the provision of a simple, reliable and inexpensive means operable in accordance with the amount of kinetic energy of the circuit breaker parts for absorbing their energy to prevent rebound of the contact structure and deformation of the parts.

My invention is an improvement upon the arrangement described in co-pending application Serial No. 98,276, filed August 28, 1936, by William Deans and assigned to the assignee of the present invention.

In accordance with my invention, the energy stored in the movable parts of the circuit breaker is absorbed by friction developed between members movable relatively to each other. By absorbing their energy, the movable parts are rapidly decelerated and brought to standstill. The time required to open the circuit is not decreased since the deceleration of the parts occurs only after the movable contact structure has moved substantially to its open circuit position.

My invention is particularly useful in connection with circuit breakers of relatively large current-carrying capacity where the parts, because of the masses of metal necessary to carry the normal, and to withstand overload, currents, are necessarily heavy, and the opening speed is high. Accordingly, with relatively heavy parts moving at high speed, the energy dissipated by suddenly arresting movement of the parts, as by striking a fixed stop, which may be a part of the frame or one of the pivot pins of the circuit breaker, produces an impact force whose magnitude is many times that developed by a graduated but rapid deceleration of the members to standstill. As a result of the foregoing phenomena, exemplified by the use of the ordinary hammer, the repeated hammer-blows on the stopping member not only caused its deformation but also transmitted the hammer blows to the other parts of the circuit breaker, causing rapid deformation and excessive wear of their pivot pins and associated parts.

Further in accordance with my invention, hammer blows or impact forces are eliminated by securing to one of the switch members suitable friction material and arranging a second member provided with friction material for sliding movement thereover as the circuit breaker is opened. A spring normally biases one member in a position to be engaged by a movable part of the circuit breaker, the engagement taking place along an inclined surface which serves the

double function of displacing one friction member with respect to the other and of developing a substantial force which presses them against each other to increase the friction between them. My invention is particularly characterized by the provision of a crank arm one end of which is operatively associated with a friction surface in such manner as to increase with displacement the opposition offered by the friction members.

In one form of my invention the crank arm supports one end of a spring which serves to transmit and to apply to the friction members the force of the spring developed in part by their relative displacement so that the opposition to movement increases with increase of displacement and with increase in the kinetic energy of the parts.

For a more complete understanding of my invention reference may now be had to the accompanying drawings in which:

Fig. 1 is a side elevational view of a circuit breaker embodying my invention with certain parts in section and certain parts omitted;

Fig. 2 is a front elevation of a three-pole circuit breaker formed by three units of the type shown in Fig. 1;

Fig. 3 is a perspective view of the actuating member of Fig. 1;

Fig. 4 is a fractional side elevational view of the circuit breaker of Fig. 1 with some of the parts omitted and illustrates the position of the energy absorbing means after opening movement of the circuit breaker has been completed;

Fig. 5 is a perspective view of the brake blocks of Figs. 1 and 4;

Fig. 6 is a side elevation of a modified form of the brake block.

Referring to Fig. 1, I have shown my invention in one form as applied to a circuit breaker mounted upon an insulated base or panel 10 through which extend studs or terminal connectors 11 and 12 respectively connected to stationary contacts 13 and 14. To complete a circuit between contacts 13 and 14, a bridging member 15, consisting of a plurality of resilient or spring laminations, preferably of copper, is supported on a movable arm 16, itself pivotally mounted on a pivot pin 17 for movement between open and closed circuit positions. The pin 17 is supported by a pair of side plates 18, only one 50 of which is shown. To relieve the bridging member 15 from the duty of interrupting the circuit, the upper end of the arm 16 is provided with an arcing contact 19 formed of arc resistance material arranged to cooperate with an arcing con- 55

tact 18 electrically connected to the stationary contact 16. The arrangement is such that the contacts 16 and 18 are separated after separation of bridging member 16 from its associated contacts 16 and 18.

The switch or circuit breaker operating mechanism may be of the type described in U. S. Letters Patent No. 2,025,781, granted December 31, 1935, upon application of W. M. Scott, Jr.

More specifically, the arm 16 is biased for movement from a closed circuit position to an open circuit position by means of a powerful spring 22 connected at one end to a pivot pin 23 and at its other end to a suitable fixed point, as shown, to the pivot pin 21. A double system of toggles, comprising toggle links 24, 25 and 26 pivotally connected together at corresponding ends by a pivot pin 27, cooperate to hold the switch member 16 in its closed circuit position and also serve to operate it from its open to its closed circuit position. The ends of toggle links 24 and 25 remote from the pin 27 are, respectively, pivotally connected at 23 and 28 to an actuating member 29 and to the arm 16. The ends of the links 26 remote from the pin 27 are supported from fixed pivot pins 30 supported by the side plates 18.

With the parts in their closed circuit positions, as illustrated in Fig. 1, the pivot pins 27, 28 and 30 are in substantial alignment; the spring 22 tends to rotate the links 26 in a clockwise direction but their movement is prevented by the link 24, the actuating member 29 pivoted at 22, and by a latch 33 pivotally connected at 34 to member 29 and engaging a stop 35 carried by a switch operating member 36. The pivot pin 23 occupies a position just short of alignment with pivot pins 27 and 28.

The force directly applied by the spring 22 to the actuating member 29 is resisted by the latch 33 but a component thereof tends to rotate the latch 33 to its unlatched position against the bias of a relatively weak spring 33a. An auxiliary latch 37 pivotally mounted at 38 to the main latch 33 has a shoulder 39 engaging a stop 40, carried by operating member 36, to prevent release of the main latch. A second relatively light spring 37a tends to retain the auxiliary latch 37 in its latching position.

The operating member 36, biased by spring 22 through member 29 and latch 33 for rotation in a counterclockwise direction, is latched into the position shown in Fig. 1 by a latching member 41 pivoted thereto at 41a and engaging the hook-shaped end of a member 42 secured to one of the side plates 18.

To open the circuit breaker, a tripping member 43 may be manually rotated about its pivot 43a to release the latch 37 or it may be operated automatically in response to an electrical condition of the circuit. If the circuit breaker is to be opened in response to overload current of predetermined magnitude, an arm 44 pivoted at 44 may be attracted by a U-shaped magnetic structure 46 surrounding the stationary contact 14. Accordingly, when sufficient magnetic flux is produced by the flow of current through the circuit breaker, the arm 44 is rotated in a clockwise direction to move the tripping member 43 against the auxiliary latch 37. Upon exertion of the slight amount of force necessary to release the auxiliary latch, the main latch 33, already biased to a releasing position, frees the movable contact structure for movement to its open circuit position.

Upon release of the latch 33 the powerful spring

22, acting directly upon the knee-pivot pin 23 of the toggle comprising link 24 and member 28 moves the pin 23 toward the panel 10 and a strong component of its force rotates the links 26 in a clockwise direction to move the arm 16 in a 5 clockwise direction and towards its open circuit position. Combined with the opening force of the spring 22, to produce extremely high speed movement of arm 16 and contacts 16 and 18 to open circuit position, are the forces due to the 10 resilience of the movable contacts and/or their supports.

Circuit breakers of the type here under consideration may be designed to carry current of magnitudes upwardly of 8000 amperes at 600 15 volts and to interrupt a possible short-circuit current of 400,000 amperes. Consequently the parts are relatively heavy to provide sufficient mechanical strength and to carry or withstand large values of current.

Because of the relatively heavy mass of the arm 16 and its associated movable parts, it will be readily understood the kinetic energy of those parts during opening of the switch is proportional to the square of their respective speeds. 20 Moreover, since the maximum speed occurs as the movable contact structure 15, 16, 18 reaches its fully open position, the kinetic energy of the movable structure is greatest as it reaches its limit of movement. Heretofore the impacts, or 25 blows, delivered to stationary stops, in arresting movement of the contact structure, have caused deformation of the stop members as well as deformation or excessive wear of the pivoted portions of the movable parts. The result was a short- 30ened life of the mechanism. There was also a tendency of the parts to rebound, in some cases sufficiently to return the contact structure substantially to its closed circuit position. The result was rapid burning of the contact surfaces 40 and a failure of the circuit breaker to interrupt the overload or short circuit current in a time short enough to prevent damage to the conductors or to devices connected in the circuit.

In accordance with the present invention, the 45 energy of the moving parts of the circuit breaker as they approach their limit of movement towards circuit opening position is rapidly dissipated as work required to move friction surfaces relative to each other. In this manner the moving parts are rapidly decelerated and brought to standstill without decreasing the opening speed of the circuit breaker. Deformation of parts, excessive wear, and tendency of the parts to rebound are substantially and effectively eliminated. The 50 latter feature, as pointed out above, becomes important when short circuit currents are interrupted because any return movement of the contact members toward closed position decreases the air gap between the contact structures and 55 may delay extinguishment of an arc drawn between the contacts, or may result in re-ignition of an arc.

As shown, the energy absorber and dissipater comprises a brake block or friction member 50 having secured to its upper and lower surfaces 65 friction elements 51 and 52 formed of woven fabric impregnated with a phenolic condensation product though a good grade of automobile, or other type of, brake lining material may be used. The block 50 is arranged for sliding movement between two upstanding arms 54 and 55, Fig. 3, formed integrally with the actuating member 29, the surface 29a between the upstanding arms being machined to provide a smooth surface with 75

which the friction element 51 cooperates. If desired, however, the surface 28a may be rough or otherwise formed to increase the frictional resistance.

- 5 One end of the block 50 is wedge-shaped, that is to say, it has an inclined face 50a while its opposite end is recessed to form a spring-seat for one end of the compression spring 56. The opposite end of the compression spring is mounted upon a spring seat carried by the lower end 51a of a crank arm 51 pivotally secured at 58 to the arms 54 and 55. The opposite end 51b of the crank arm nests within a notch provided in a plate 59 which slidably engages the friction element 52. It will be observed the spring 56 normally biases the block 50 to a position in spaced relation from the end 51a of the crank arm, or to a position near one, the forward, end of the surface 28a.
- 20 The surface 50a is preferably inclined at an angle of approximately 52° with respect to the plane friction surfaces of elements 51 and 52, although the angle of surface 50a may vary substantially; for example, it may have a value 25 between 40° and 70°, though for special cases it may be selected either above or below these limits. As shown in Fig. 6, the block 50 may be provided with a curved surface 50c formed so that lines tangent thereto form angles with the 30 friction surfaces which vary from about 70° to about 40° as they approach the lower part of member 50.

Again referring to the operation of the circuit breaker to the open position, it will be remembered that as pivot pins 23 and 27 move inwardly toward the panel 10, the actuating member 29 rotates in a counterclockwise direction, and the switch arm 16 moves rapidly in a clockwise direction towards its open circuit position. As the 40 rounded surface 16a approaches the brake block or friction member 50, the parts are arranged so that engagement between the two surfaces 16a and 50a occurs at the upper or rearward portion of inclined face or surface 50a. Subsequent movement of surface 16a upon the inclined face 50a displaces the brake block 50 and applies to it a substantial force in a direction to press it against the plane surface 29a of the actuating member. The drag exerted upon plate 59 by 45 movement of friction material 52 is in a direction to rotate the crank arm 51 in a direction to increase the pressure on the block 50. As shown in Fig. 4, as the crank rotates in a counterclockwise direction, the force due to this effect becomes very great. The crank, due to the proportioning of its parts, has a toggle-like or wedging action; that is to say, the braking force applied to the block is many times greater than the force of the drag which energizes the crank. 50 The spring 56, by displacement of the brake block 50, is compressed and by means of crank arm 51 applies a pressure to the plate 59 simultaneously to increase the frictional resistance offered by the energy dissipater. Accordingly, 55 the block is self-energized; that is, large friction forces are produced which do not depend upon the inclination of surface 50a. Moreover, when the parts are moving at greater speed, greater forces are exerted between the friction surfaces to increase the amount of energy absorbed. Specifically, the component of force, due to the inclined surface 50a, which presses block 50 against member 29 increases with increase in kinetic energy. Thus higher speeds of the parts result in 60 greater rates of acceleration of block 50 caused

by an increased force applied by surface 16a to surface 50a.

Energy absorbing and dissipating devices constructed as aforesaid have proved to be entirely satisfactory to bring the moving parts of a circuit breaker to a standstill with minimum shock. Impact forces or hammer-blows upon the pivotal connections were substantially entirely eliminated.

Continuing with the operation of the circuit breaker, as the switch arm 16 reaches its fully opened position, the brake block 50, by reason of its displacement, has so greatly increased the pressure upon the friction surfaces, it is definitely brought to standstill; that is to say, the friction forces after substantial displacement of the block 50 become so great, the block 50 itself acts as a rigid stop, but since the major portion of the kinetic energy has already been absorbed, it is not, when acting as a stop, subject to blows 20 of a deforming or damaging magnitude. If some deformation of the inclined face or surface 50a occurs, operation of the circuit breaker is in no way affected. Moreover, when necessary, the block 50 may be readily and economically replaced, although such replacement is seldom necessary.

As shown in Fig. 6, the inclined surface 50a is to advantage curved somewhat at its upper end so that the surface 16a initially causes a 30 relatively small displacement of block 50. The same result may be approximated by selecting the spring 56 with characteristics such that substantial initial compression of the spring does not transmit forces to the crank arm as large as 35 for later compression of the spring. For example, several turns of the spring, particularly those within the recessed end of the block 50, may be of less diameter than the remaining turns of the spring. With such an arrangement the 40 initial force transmitted would be much less per unit of change of displacement than after the time the smaller turns of the spring engage each other to start compression of the turns of the spring having the larger diameter.

The aforesaid selection of the angle of the inclined surface 50a rests upon the assumption the surface 16a moves in a substantially straight line across and normal to the surface 50a. If the co-operating surface, as surface 16a, approaches 50 through a different path, the angle of surface 50a is selected to produce the desired displacement.

Preparatory to reclosure of the circuit breaker the latch 41 of the operating member 36 is released, during opening of the circuit breaker, by movement of a projection or roller 63, carried by member 29, over a cam surface 41b.

In order to reclose the circuit breaker an operating handle 62, secured to the operating member 36, is rotated in a counterclockwise direction until the stop 35 is moved into a position again to be engaged by the main latch 33, this engagement being effected by the bias of the spring 33a. At the same time the auxiliary latch 31 and the operating member 36 are effectively secured to the actuating member 29 so that by returning the handle 62 and member 36 to their original positions, the circuit breaker is reclosed.

Upon initial movement of the actuating member 29 in a clockwise direction, the spring 56 is effective to move the friction member of brake block 50 towards its original or normal position. In this connection, movement of block 50 towards its original position exerts a drag on the crank 75

57 in a direction tending to decrease the pressure by the crank applied to the block.

If the spring 56 is sufficiently strong, it may, after opening of the circuit breaker, rotate the actuating member 29 in a clockwise direction to return the brake block 50 to its original position. At any rate the brake block 50 is returned to its original position prior to reclosure of the circuit breaker. Thus the energy absorber and dissipater is effective, should the circuit breaker be tripped during the reclosing operation, to prevent shock and injury to the parts.

The circuit-closing operation is complete as soon as the latch 41 engages the member 42, although, as indicated, the circuit breaker is trip-free; that is, it may be automatically opened irrespective of, and without interference from, the operating member 36 and its associated handle 62.

From the foregoing it will be readily apparent that my invention is applicable to circuit breakers of any number of poles. For example, in Fig. 2 I have shown a three-pole circuit breaker, each pole being identical with the one shown in Fig. 1. The actuating members 29 of each pole are connected together by a common cross-member 65. Similarly the trip members 43 are secured together by a cross-member 66. The foregoing arrangement insures that an overload upon one of the poles of the circuit breaker is effective to trip all of the poles thereof to open circuit position.

The circuit breaker may be manually opened by means of a tripping member 67 secured to the cross-member 66.

While I have shown a particular embodiment of my invention, it will be understood, of course, that I do not wish to be limited thereto, since many modifications may be made, and I therefore contemplate by the appended claims to cover any such modifications as fall within the spirit and scope of my invention.

What I claim is:

1. In a circuit breaker having contact structures one of which is moved relative to the other from a closed to an open circuit position, the combination of friction means comprising solid bodies in sliding contact with each other for opposing opening movement of said movable structure, and mechanical means for increasing as a function of the speed and displacement of said movable structure the opposition offered by the friction produced by the sliding contact between said solid bodies to said opening movement of said movable structure.

2. In a circuit breaker having contact structures one of which is moved relative to the other from a closed to an open circuit position, the combination of friction means comprising solid bodies in sliding contact with each other for opposing opening movement of said movable structure, and mechanical means operable by said movable structure for continuously increasing the opposition to said opening movement of said movable structure by the friction produced by the sliding contact between said solid bodies.

3. Means for absorbing the energy of the movable parts of a circuit breaker incident to their movement from a closed to an open circuit position comprising a pair of relatively movable members one of which is provided with a friction surface slidable with respect to the surface of the other member, means operable by one of the parts of said circuit breaker for displacing one of said members with respect to the other, and

mechanical means operable in accordance with the displacement of said one member for pressing said surfaces against each other with a pressure which rises with the extent of displacement of said one member.

4. Means for absorbing the energy of the movable parts of a circuit breaker incident to their movement from a closed to an open circuit position comprising relatively movable members, one of which is provided with a friction surface slid- 10 able over a surface of the other member, means operable by one of the parts of said circuit breaker for displacing one of said members with respect to the other, means operable with a wedging action by one of said members to press said friction surfaces against each other, and means for further increasing the pressure upon said surfaces in accordance with the displacement between said members.

5. Means for absorbing the energy of the movable parts of a circuit breaker incident to their movement from a closed to an open circuit position comprising a pair of switch members having friction surfaces, one of which is slidable with respect to the other, and mechanical means energized 25 from one of said members for applying a pressure on said friction surfaces which increases in accordance with the extent of displacement between said members.

6. Means for absorbing the energy of the movable parts of a circuit breaker incident to their movement from one position to another comprising a member provided with a friction surface, means slidably mounting said member upon one of the parts of said circuit breaker, said member 20 being provided with an inclined surface arranged to be engaged by another part of said circuit breaker for displacement of said member as the movable parts approach one of their limits of movement, a crank arm, one portion of which cooperatively engages said member to press said friction member against said cooperating surface, and a spring, associated with the other end of said crank arm, operable on displacement of said member for pressing said first-named end of said 40 crank arm against said member to increase the pressure between said surfaces.

7. Means for absorbing the energy of the movable parts of a circuit breaker incident to their movement from one position to another comprising 50 a member provided with friction surfaces on opposite sides thereof, means having a cooperating surface over which one of said friction surfaces is slid- 55 able, a brake block engaging the other of said friction surfaces, a crank arm, one end of which cooperates with said block, a spring associated with the opposite end of said crank arm and operable by displacement of said member for simultaneously pressing said brake block and said adjoining friction surfaces against each 60 other.

8. In a circuit breaker provided with a movable switch member, actuating means therefor, the combination of means for absorbing the energy of the movable parts of the circuit breaker 65 incident to their movement from a closed to an open circuit position, comprising a member having a surface slidable along a surface of said actuating member, at least one of said surfaces comprising friction material, means operable by 70 one of the parts of said circuit breaker for displacing said member with respect to said actuating member, and mechanical means for pressing said surfaces against each other with a pressure which increases during displacement of said 75

member and which is substantially reduced upon disengagement of said member and said displacing means.

9. Means for absorbing the energy of the movable parts of a circuit breaker incident to their movement from one switching position to another comprising a switch member having a friction surface, a second switch member having a cooperating friction surface and an inclined face adjacent one end thereof engageable by one of said parts of said circuit breaker for displacement of said friction surfaces, and means for pressing said surfaces against each other with a pressure which increases with relative displacement of said surfaces.

10. Means for absorbing the energy of the movable parts of a circuit breaker incident to their movement from one switching position to another comprising a switch member having a friction surface, a second switch member having a cooperating friction surface and an inclined face adjacent one end thereof engageable by one of said parts of said circuit breaker for displacement of said friction surfaces, a crank arm having its respective ends cooperatively associated with said switch members, and a compression spring interposed between one end of said crank arm and said second switch member for increasing the pressure between said surfaces in accordance with the extent of displacement of said second switch member relative to said first-named switch member.

11. Means for absorbing the energy of the movable parts of a circuit breaker incident to their movement from one switch position to another comprising a switch member having a friction surface, and an inclined face adjacent one end thereof engageable by one of said parts of said circuit breaker for displacement of said friction surfaces, a crank arm having its respective ends cooperatively associated with said switch members, and a compression spring interposed between one end of said crank arm and said second switch member for increasing the pressure between said surfaces in accordance with the extent of displacement of said second switch member relative to said first-named switch member, said spring upon disengagement of said inclined face from said part of said circuit breaker returning said second switch member to its original position.

12. In a circuit breaker, an operating member for closing the circuit breaker, a means for opening the circuit breaker, said operating member having a friction surface, a brake block having a cooperating friction surface, a crank arm, one end of which cooperates with said block to press said surfaces against each other, one end of said block having an inclined face engageable by a movable part of said circuit breaker for displacing one of said surfaces relative to the other, and a compression spring supported between the opposite end of said block and the opposite end of said crank arm.

13. In a circuit breaker having movable contact structure movable to an open circuit position, an operating member, a toggle interposed between said member and said structure and movable to a collapsed position, means operable, upon movement of said contact structure to open position, to move said operating member towards said structure, the combination of means for absorbing the energy of the moving parts of said circuit breaker comprising a brake block having a friction surface slidably movable over a cooperating friction surface of said operating member,

one end of said block having an inclined surface, means biasing said block to a position where an upper portion of said inclined surface is engaged by said contact structure as the latter approaches its open circuit position, further movement of said structure displacing one of said friction surfaces relative to the other, and a crank arm pivoted to said operating member, one end of said arm cooperatively engaging said brake block and the other end of said arm disposed adjacent the end of said brake block opposite its inclined surface, said biasing means including a compression spring interposed between said brake block and said last-named end of said crank arm.

14. In a circuit breaker having contact structure movable at high speed from one position to another and an operating member for operating said contact structure to said one position, the combination of means for absorbing the energy of the movable parts of said circuit breaker during its high speed operation comprising a brake block having a pair of friction surfaces and an inclined surface at one end thereof and between said friction surfaces, said operating member having a plane surface disposed between upwardly extending arms thereof and cooperating with one of said friction surfaces, a crank arm pivoted between said arms, a compression spring interposed between one end of said crank arm and said brake block, and a pressure plate interposed between the other end of said crank arm and the other of said friction surfaces, one of said movable parts engaging said inclined surface during said high speed operation to displace said block and to compress said spring.

15. Energy absorbing means for a circuit breaker comprising a brake block, opposite surfaces of which are lined with friction material, one end portion of which is wedge-shaped and a spring seat at the opposite end thereof, a movable part of said circuit breaker having at least one surface over which said brake block is slidable, a crank arm pivoted to said movable part, a spring supported between said spring-seat and one end of said crank arm for biasing the opposite end of said crank arm against said block, and means engaging said wedge-shaped end to move said friction surfaces relative to said movable part and to compress said spring, said crank arm transmitting the force of said spring to said block to increase the pressure upon said surfaces in accordance with the extent of relative movement of said surfaces.

16. A circuit breaker comprising fixed contact structure, a movable system including cooperating contact structure movable to open circuit position, means for braking said movable contact structure comprising a braking member frictionally engaging and movable with respect to a cooperating member, brake-actuating means included in said movable system engaging and actuating said first-named braking member with application thereto of a force having a component acting upon said first-named braking member in direction substantially corresponding with the direction of its movement with respect to its said cooperating member, and mechanical means actuated by said first-named braking member for transmitting said force component and redirecting application thereof to said first-named braking member to increase its pressure upon its said cooperating member.

17. A circuit breaker comprising fixed contact structure, a movable system including cooperating contact structure movable to open circuit position.

- means for braking said movable contact structure comprising a braking member frictionally engaging and movable with respect to a cooperating member, brake-actuating means included in said movable system engaging and actuating said first-named braking member with application thereto of a force having components, one of which acts upon said first-named braking member in direction to increase its pressure upon its said cooperating member, and another of which acts upon said first-named braking member in direction substantially corresponding with the direction of its movement with respect to its said cooperating member, and mechanical means actuated by said first-named braking member for transmitting said second-named force component and redirecting application thereof to said first-named braking member to increase its pressure upon its said cooperating member.
18. A circuit breaker comprising fixed contact structure, a movable system including cooperating contact structure movable to open circuit position, means for braking said movable contact structure comprising a braking member frictionally engaging and movable with respect to a cooperating member, brake-actuating means included in said movable system engaging and actuating said first-named braking member with application thereto of a force whose magnitude is dependent upon the speed at which said movable system moves to open circuit position and having a component acting upon said first-named braking member in direction substantially corresponding with the direction of its movement with respect to its said cooperating member, and mechanical means actuated by said first-named braking member for transmitting said force component and redirecting application thereof to said first-named braking member to increase its pressure upon its said cooperating member.
19. A circuit breaker having fixed contact structure, a movable system including cooperating contact structure movable to open circuit position, comprising a braking member frictionally engaging and movable with respect to a cooperating member, brake-actuating means included in said movable system engaging and actuating said first-named braking member with application thereto of a force whose magnitude is dependent upon the speed at which said movable system moves to
- open circuit position and having components, one of which acts upon said first-named braking member in direction to increase its pressure upon its said cooperating member, and another of which acts upon said first-named braking member in direction substantially corresponding with the direction of its movement with respect to its said cooperating member, and mechanical means actuated by said first-named braking member for transmitting said second-named force component and redirecting application thereof to said first-named braking member to increase its pressure upon its said cooperating member.
20. In a circuit breaker having fixed contact structure and a movable system including cooperating contact structure movable to open circuit position, the combination of a braking member frictionally engaging and movable with respect to a cooperating member, brake-actuating means included in said movable system engaging and displacing said first-named member relative to its cooperating member after substantial circuit-opening movement of said system, and means including a pivoted arm operable by said displacement for increasing the pressure between said members rapidly to increase the braking effort opposing opening movement of said system, and means operable during circuit-closing movement of said system for producing a return movement of said first-named member, said means including said pivoted arm upon initiation of said return movement being effective greatly to reduce the braking effort opposing said return movement.
21. In a circuit breaker having a movable system including contact structure biased to open circuit position, the combination of cooperating braking members at least one of which is displaceable with respect to the other member, brake-actuating means included in said system engaging and producing said displacement of said one member, and means for increasing the braking effort quickly to bring said system to standstill comprising a pivoted arm for pressing said members against each other, means exerting a frictional drag upon one end of said arm to produce with respect to its pivot a toggle-like or wedging action greatly to increase with said displacement the pressure of said members, one against the other.

CERTIFICATE OF CORRECTION.

Patent No. 2,137,001.

November 15, 1938.

GEORGE A. HEALIS.

It is hereby certified that error appears in the printed specification of the above numbered patent requiring correction as follows: Page 5, first column, line 37, claim 11, after the comma and before the word "and" insert --a second switch member having a cooperating friction surface--; page 6, second column, line 38, claim 21, for "member" read --members--; and that the said Letters Patent should be read with this correction therein that the same may conform to the record of the case in the Patent Office.

Signed and sealed this 28th day of January, A. D. 1941.

Henry Van Arsdale,
Acting Commissioner of Patents.

- means for braking said movable contact structure comprising a braking member frictionally engaging and movable with respect to a cooperating member, brake-actuating means included in said movable system engaging and actuating said first-named braking member with application thereto of a force having components, one of which acts upon said first-named braking member in direction to increase its pressure upon its said cooperating member, and another of which acts upon said first-named braking member in direction substantially corresponding with the direction of its movement with respect to its said cooperating member, and mechanical means actuated by said first-named braking member for transmitting said second-named force component and redirecting application thereof to said first-named braking member to increase its pressure upon its said cooperating member.
18. A circuit breaker comprising fixed contact structure, a movable system including cooperating contact structure movable to open circuit position, means for braking said movable contact structure comprising a braking member frictionally engaging and movable with respect to a cooperating member, brake-actuating means included in said movable system engaging and actuating said first-named braking member with application thereto of a force whose magnitude is dependent upon the speed at which said movable system moves to open circuit position and having a component acting upon said first-named braking member in direction substantially corresponding with the direction of its movement with respect to its said cooperating member, and mechanical means actuated by said first-named braking member for transmitting said force component and redirecting application thereof to said first-named braking member to increase its pressure upon its said cooperating member.
19. A circuit breaker having fixed contact structure, a movable system including cooperating contact structure movable to open circuit position, comprising a braking member frictionally engaging and movable with respect to a cooperating member, brake-actuating means included in said movable system engaging and actuating said first-named braking member with application thereto of a force whose magnitude is dependent upon the speed at which said movable system moves to
- open circuit position and having components, one of which acts upon said first-named braking member in direction to increase its pressure upon its said cooperating member, and another of which acts upon said first-named braking member in direction substantially corresponding with the direction of its movement with respect to its said cooperating member, and mechanical means actuated by said first-named braking member for transmitting said second-named force component and redirecting application thereof to said first-named braking member to increase its pressure upon its said cooperating member.
20. In a circuit breaker having fixed contact structure and a movable system including cooperating contact structure movable to open circuit position, the combination of a braking member frictionally engaging and movable with respect to a cooperating member, brake-actuating means included in said movable system engaging and displacing said first-named member relative to its cooperating member after substantial circuit-opening movement of said system, and means including a pivoted arm operable by said displacement for increasing the pressure between said members rapidly to increase the braking effort opposing opening movement of said system, and means operable during circuit-closing movement of said system for producing a return movement of said first-named member, said means including said pivoted arm upon initiation of said return movement being effective greatly to reduce the braking effort opposing said return movement.
21. In a circuit breaker having a movable system including contact structure biased to open circuit position, the combination of cooperating braking members at least one of which is displaceable with respect to the other member, brake-actuating means included in said system engaging and producing said displacement of said one member, and means for increasing the braking effort quickly to bring said system to standstill comprising a pivoted arm for pressing said members against each other, means exerting a frictional drag upon one end of said arm to produce with respect to its pivot a toggle-like or wedging action greatly to increase with said displacement the pressure of said members, one against the other.
